INTERLOCKING SYSTEM FOR RAILROADS

Charles S. Bushnell, Rochester, N. Y., assignor
to General Railway Signal Company, Roche-
ster, N. Y.

Application April 8, 1936, Serial No. 73,322

19 Claims. (Cl. 246—134)

This invention relates to an interlocking system of the free lever type for railroads, and more particularly to an interlocking system of the entrance-exit type in which a route is defined by operating a button at the entrance to such route on a miniature track layout and by operating another button at the exit end of the route on such miniature track layout.

Since, in most interlocking systems, the number of routes that may be set up greatly exceeds the number of entrance points to such routes, a considerable saving in manually operable devices and considerable simplification results if a particular route is defined by designating its beginning and its end, and without giving any consideration to the track switches involved therein. Also, if an operator has before him a miniature track layout corresponding to the actual track layout, it is believed to be easier for the operator to set up a route through the plant by operating buttons from point to point over the route through his miniature track layout than it would be to operate a particular lever to define such route or to operate a lever for each signal and switch in such route. The present invention contemplates operating a button at a point on the miniature track layout defining the entrance to a route preferably called an entrance button, and thereafter operating a button on such miniature track layout defining the exit end of such route and preferably called an exit button. Insofar as this entrance-exit manipulation is concerned, the present invention is an improvement over the systems disclosed in the prior applications of S. N. Wight Ser. No. 721,696 filed April 21, 1934 and Serial No. 69,905 filed March 20, 1936.

More specifically, it is proposed in accordance with the present invention to employ in connection with the miniature track layout a polar route end relay for each end of each route, and to preferably provide a rotatable entrance button which may be left in its operated position to pick up the polar relay to a particular polar position at the entrance of the route to be selected, to pick up the polar relay at the exit end of the route in the same polar direction by a push exit button which will return to its normal position when released, and to provide a stick circuit for this latter relay which will stick up through a front contact of the former relay only if the track switch control relays are in a position to define the particular route defined by these relays. The polarity of energization of these relays defines the direction of train travel over such route. In

addition, it is proposed to provide a route circuit to clear a signal over such route only in the event that the track switches have actually responded to set up the route defined by the two energized route end relays.

Another feature of the present invention resides in the provision of a polar switch machine control relay which may be energized either through circuits controlled by the route end relays defining the entrance and exit ends of a route including the track switch or may be controlled in case of emergency by circuits controlled by a switch machine lever, the organization of circuits being such that if the switch machine control relay is once energized it cannot be energized to a reverse polar position unless such relay is first allowed to assume the deenergized position. This novel switch machine control relay and its coordination of the circuits constitutes one of the interlocking features of the present invention.

Other objects, purposes and characteristic features of the invention will in part be pointed out in the specification hereinafter and will in part be obvious from the accompanying drawings, in which:—

Fig. 1A shows conventionally the apparatus located in an office or tower; and

Fig. 1B shows the actual track layout in the field and which corresponds to the miniature track layout in the office and if Figs. 1A and 1B are laid end to end they show the selected embodiment of the invention as to the entire interlocking system.

Apparatus in the field

Let us refer to Fig. 1B in which there has been illustrated conventionally a rather simple form of interlocking track layout which in practice may take a much more complicated form, and which comprises tracks 1 and 2 connected by cross-overs 6 and 7 to afford four routes from left to right exclusive of the run-around route over both cross-overs 6 and 7 reversed, making a total number of five routes from left to right and an additional five routes from right to left, or a total of ten routes. It is of course understood that these routes may also include switches which are not part of a cross-over, and that each cross-over may be considered as two switches. The track sections 1 and 2 as well as the cross-overs 6 and 7 are insulated as shown by insulating joints 8, to permit the application of the usual track circuits, of which a track circuit containing track relay T1 and battery 9 and a track circuit

containing track relay T2 and track battery 10 only have been illustrated.

At the entrance for each east-bound route starting on track 1 is shown a signal S¹, for each 5 eastbound route starting on track 2 a signal S², for each west-bound route starting on track 1 a signal S³, and for each west-bound route starting on track 2 a signal S⁴. The signal for continuing an east-bound route on the track 1 has 10 been designated S⁵. As illustrated the crossovers 6 and 7 may be operated by switch machines SM6 and SM7, respectively. Although these switch machines may be of any suitable construction they are preferably of a construction 15 as shown in the prior patent to Howe No. 1,466,903 dated September 4, 1923. These switch machines preferably include point detector contacts which are closed only if the switch points are actually in a particular extreme position and 20 locked, and although these switch point detectors may be of any suitable construction they are preferably of a construction as shown in the prior patent to Bushnell No. 1,517,236 dated November 5, 1924. These point detector 25 contacts of switch machines SM6 and SM7 are connected to respectively control switch repeater relays WP6 and WP7, as a result of which these relays WP6 or WP7 will be energized to a particular polar position only if the corresponding 30 switch machine assumes a corresponding extreme position and is locked. These switch machines SM6 and SM7 are preferably controlled by switch machine control relays Z6 and Z7. The signals S¹, S², S³, and S⁴ are preferably 35 manually controllable by signal control relays G1, G2, G3, and G4, and may be of any suitable construction. These signals in addition to this manual control are preferably subject to automatic track circuit control, such as well 40 understood by those skilled in the art of railway interlocking, and preferably indicate a clear position if its corresponding G relay is energized and two blocks in advance of the signal are unoccupied; indicate caution if the associated G 45 relay is energized, the first block in advance is unoccupied but the second block in advance is occupied; and indicate a stop position if either the associated G relay is deenergized or the block immediately in advance of the signal is occupied; 50 all as shown in said prior application of S. N. Wight and as conventionally illustrated by dotted lines 11, 12, 13, and 14 respectively connecting the signals S¹, S², S³, and S⁴ to their respective G relays.

55 It is well understood by those skilled in the art of railway signalling and interlocking, that a power-operated switch machine should not be permitted to be operated when it is unsafe to move the switch points, and although a lock relay controlled in any of the various well known ways may be employed to prevent operation of the switch machines SM6 and/or SM7, a simple form of electric locking means for the switch machines has been illustrated in the form of 60 lock relay L. In the particular arrangement shown the lock relay L, which must be energized to allow operation of either the switch machines SM6 or SM7 and can be energized only if all of the signals S¹, S², S³, and S⁴ are at stop and the 65 two detector track relays T1 and T2 are energized and reflect non-occupancy of the track sections 1 and 2. This control circuit for the relay L may be traced from the terminal (+) of a suitable battery, through back contact 20 of 70 signal relay G3, back contact 21 of signal relay 75

G4, back contact 22 of signal relay G2, back contact 23 of signal relay G1, front contact 24 of track relay T2, and front contact 25 of track relay T1, through the winding of relay L to the other terminal (—) of said battery. The positions of these switch machines is indicated in the office by switch repeater relays WP6 and WP7, controlled by the point detectors of these switch machines in any suitable manner as indicated conventionally by dotted lines 18 and 19. 10

Apparatus in the office

In the tower or office is located a miniature track layout which corresponds in every respect to the actual track layout in the field. At the 15 entrance point to each route portion of the miniature track layout is located a suitable manually operated entrance button which is preferably of such construction that, if operated, it will remain in its operated position. These levers or buttons 20 are preferably rotatable and have been designated E¹, E², E³, and E⁴ and are used for initiating the clearing of the signals S¹, S², S³, and S⁴ respectively, located on the actual track layout. 25 These buttons E¹, etc., are preferably buttons of the rotary type which are turned to an angle of 90 degrees either to the right or to the left depending upon whether the signal they control defines traffic to the right or to the left, and in the event that the button may control one 30 signal to the right or another signal to the left, as is true of the button E³, these arrows indicate the direction in which traffic is to move over the actual track layout. In addition there is located at the exit end of each route an exit push 35 button PB (with suitable exponent). This push button PB is to reflect the exit end of the route and as will be pointed out hereinafter need be depressed only momentarily to complete the selection of a particular route or portion of a route. 40 These push buttons have been designated PB¹, PB², PB³, PB⁴, and PB^x. Each entrance button E¹ etc., has associated with it a route relay RR¹ etc., for each direction governed by such entrance button. The entrance button E³, since 45 it governs traffic in two directions has two route end relays RR³ and RR⁵ associated therewith. As illustrated these route end relays have been designated RR¹, RR², RR³, RR⁴, and RR⁵, and these relays RR¹, RR², etc. may be controlled by 50 these entrance buttons E¹ etc. or by the associated push button PB¹ etc., all in a manner as more specifically pointed out in the operation of the system hereinafter.

In the office are provided switch machine control relays SMR⁶ and SMR⁷ for controlling the field switch machine control relays Z6 and Z7 respectively. Each of these relays SMR⁶ and SMR⁷ has associated therewith a manually controllable energizing lever, such as levers SML⁶ and SML⁷. 60 These levers SML⁶ and SML⁷ normally assume their middle inactive position, and when in such position allow the associated relay to be controlled by any one of a plurality of circuits, each circuit of which includes the front contacts of 65 two route end relays RR (having exponents defining the ends of the route) in series. These relays SMR⁶ and SMR⁷ are electrically connected to their associated emergency levers and to the energizing circuits through front contacts of 70 these route end relays so that if one of these relays SMR⁶ or SMR⁷ is once energized it cannot be operated to a different polar position without first causing deenergization of the relay, and the structure is such that the emergency lever can- 75

not break a route end relay energized circuit which is in conflict with the then position of such lever. This feature is employed so that if a route has once been set up through the medium of the 5 route end relays, this route cannot be disturbed by operation of the manually operable switch machine lever, such as lever SML⁶ or SML⁷, to a conflicting position. In addition to the tower apparatus already described there are also provided route circuits for energizing the various 10 signal relays G¹, G², G³, and G⁴ in the field, the nature and function of these circuits will be more specifically described in the operation of the system hereinafter.

15

Operation

Let us assume that the operator wishes to clear an east-bound route extending from signal S¹ to signal S³. In order to do this he will operate the 20 entrance button E¹ to the right, so that the arrow thereon points eastwardly, and he will thereby energize the upper winding of the relay RR¹ through the following circuit:—beginning at the terminal (+) of the office battery, contact 63 of 25 entrance button E¹ assuming its left-hand position, upper winding of the relay RR¹ and normally closed push button contact 33 of the push button PB¹. The current in this circuit will be of a polarity to operate the polar contact 27 to 30 the right, and if it not already assumes the right-hand position will operate it there and will pick up the neutral contacts 28 and 29. The operator will next depress the push button PB³, and in so doing will energize the upper winding of the relay RR³ through the following energizing circuit:—beginning at the terminal (+) of the 35 office battery, back contact 38 of the push button PB³, upper winding of the relay RR³, through normally closed contact 43 of entrance button E³ to the other terminal (—). This current is of a polarity to operate the polar contact 30 of relay RR³ to the right-hand position, and unless it already assumes the right-hand position will so operate it, and will also close the front contacts 40 45 31 and 32 of this relay.

With the route end relays RR¹ and RR³ energized, the relay SMR⁶ is energized to its normal energized position through the following circuit:—beginning at the terminal (+) of the battery, front contact 34 of the relay RR³, front contact 35 of the relay RR¹, normally closed contact 36 of the emergency lever SML⁶, normal winding N of the relay SMR⁶, back contact 37 of the relay SMR⁶ to the terminal (—). Closure of 50 55 this energizing circuit causes relay SMR⁶ to move its polar contacts to the right and to pick up and close its neutral front contacts and break its neutral back contacts. Similarly, the following energizing circuit for the relay SMR⁷ is closed with 60 relays RR¹ and RR³ energized:—beginning at the terminal (+) of the office battery, front contact 39 of the relay RR¹, front contact 40 of the relay RR³, normally closed contact 41 of the emergency lever SML⁷, normal winding N of the relay 65 SMR⁷ through back contact 42 of the relay SMR⁷ to the other terminal (—) of said battery. The closure of this circuit will cause the relay SMR⁷ to move its polar contacts to the proper position and close its front neutral contacts and open its 70 back neutral contacts. It may be pointed out here that the relays SMR⁶ and SMR⁷ are not called upon to pick up through their own back contacts, for each back contact has in multiple therewith a polar contact and since the polar 75 contacts of a polar-neutral relay operate quicker

than the neutral contacts the stick circuit is maintained through the polar contact before the pick-up circuit is broken.

With the neutral contacts 44 and 47 of the 5 relays SMR⁶ and SMR⁷ closed, and with the relay RR³ temporarily maintained energized by the operator's depression of the push button PB³, the following stick circuit for the relay RR³ is closed:—beginning at the terminal (+) of the office battery, front contact 28 of the relay RR¹, polar contact 27 of the relay RR¹ to the right, contacts 44 and 45 of the relay SMR⁶, contacts 46 and 47 of the relay SMR⁷, contacts 30 and 32 of the relay RR³, through the lower winding of this relay RR³ to the other terminal (—) of the 10 said battery. It will be noted that the circuit just traced is a stick circuit for the relay RR³ because it includes the stick contact 32. The operator may now release the push button PB³, the relay RR³ remaining held energized through 15 this stick circuit.

With the switch machine control relays SMR⁶ and SMR⁷ both energized with their polar contacts to the right, the switch control relays Z⁶ and Z⁷ will be energized by current of a polarity 20 to operate or maintain the switch machines SM⁶ and SM⁷ in their normal position. Also, with the track switches 6 and 7 both assuming their normal position, and with their switch points locked, the switch repeater relays WP⁶ and WP⁷ will be 25 energized to reflect the normal condition of the cross-overs 6 and 7, namely, will be energized with their polar contacts to the right and with their neutral front contacts closed. With the relays RR¹, WP⁶, WP⁷, and RR³ all energized to the 30 right, the following circuit for energizing the signal relay G¹ is closed:—beginning at the terminal (+) of a suitable battery, normally closed contact 50 of the push button PB³, polar contact 51 and neutral contact 52 of the relay RR³, neutral contact 53 and polar contact 54 of the relay WP⁷, polar contact 55 and neutral contact 56 of the relay WP⁶, neutral contact 57 and polar contact 58 of the relay RR¹, wire 59, winding of the relay G¹ to the other terminal (—) of the same 35 source. With the relay G¹ energized and providing traffic conditions in advance of the signal S¹ are clear, the signal S¹ will be cleared to permit traffic to move over the track section 1 from the signal S¹ to the signal S³. After the train which 40 is to move over the track section 1 has moved beyond the signal S³, the operator may return the entrance button E¹ to its normal position as a result of which the relay RR¹ will be deenergized and will by opening of its neutral contact 28 interrupt the stick circuit for the relay RR³ resulting in deenergization of this relay RR³. Similarly, dropping of contacts 35 and 39 of the relay RR¹ will result in deenergization of the 45 switch machine control relays SMR⁶ and SMR⁷, and similarly dropping of contacts 57 of relay RR¹ will result in deenergization of the signal control relay G¹, thereby placing the signal S¹ in its stop condition.

It is readily noted that if the operator desires 50 to move traffic from right to left over the same track section 1, he will operate the entrance button E¹ to the left thereby energizing the relay RR³ to the left. Similarly, he will next depress the push button PB¹ resulting in energization of the 55 relay RR¹ to the left, as a result of which the relay RR¹ may be stuck up through its stick contact 29 through the same route reflecting contacts 44, 45, 46, and 47, through the front contact 31 of the relay RR³. The switch machine 60

control relays SMR⁶ and SMR⁷ will, of course, be again energized to the right for the same reasons as already explained, this because the same route relays are energized for the same route irrespective of whether traffic is to move from right to left or from left to right. Since, however, the route end relays RR¹ and RR³ are now energized to their left-hand position, the signal relay G3 is energized instead of the signal relay G1. This energizing circuit for the signal relay G3 may be traced as follows:—beginning at the terminal (+) of the office battery, normally closed contact 61 of the push button PB¹, polar contact 58 and neutral contact 57 of the relay RR¹, neutral contact 56 and polar contact 55 of the switch repeater relay WP6, polar contact 54 and neutral contact 53 of the switch repeater relay WP7, neutral contact 52 and polar contact 51 of the route end relay RR³, wire 62, winding of the relay G3 to the other terminal (—) of said battery. With the relay G3 energized the signal S³ will assume a clear, caution or stop condition depending on traffic conditions in advance of such signal. Obviously, the return of the entrance button E³ to its normal position will result in deenergization of the route end relays RR³ and RR¹ and in turn will result in deenergization of the relay G3 and will place the signal S³ back in its stop condition.

In the same manner as just explained in connection with track section 1, traffic may be set up from left to right or from right to left over the track section 2, and for this reason like contacts associated with the apparatus of track section 2 have been assigned reference numbers that are higher by forty than the reference characters applied to corresponding devices of the route over track section 1.

Let us now assume that the operator wishes to allow a train to move from a point to the rear of signal S¹ on section 1 to a point to the right of signal S⁴ on the section 2. To set up this route the operator will turn the entrance button E¹ to the right, thereby resulting in energization of the relay RR¹ to the right, for reasons already given. The operator will then depress the push button PB⁴ as a result of which the relay RR⁴ will be energized through a circuit beginning at the terminal (+) of a battery, through back contact 78, through the upper winding of relay RR⁴, through the contact 83 of the entrance button E⁴, to the other terminal (—) of the same battery, as a result of which the relay RR⁴ will be energized until the push button PB⁴ is released.

With the route end relays RR¹ and RR⁴ now energized the switch machine relay SMR⁷ will be energized negatively, that is, so as to operate its polar contacts to the left through the following energizing circuit:—beginning at the terminal (+) of the office battery, front contact 105 of the route relay RR¹, front contact 106 of the route end relay RR⁴, normally closed contact 107 of the emergency switch machine lever SML⁷, the reverse winding R of the relay SMR⁷, through the back contact 108 of the relay SMR⁷, to the other terminal (—) of said battery. The polar contact 109 of the relay SMR⁷ will operate more quickly than will the neutral contact 108, so that the energizing circuit will be shifted from the contact 108 to the contact 109. With the relay SMR⁷ now energized to the left, and with the relay SMR⁶ now energized to the right through a circuit including front contact 74 of relay RR⁴, and front contact 35 of relay RR¹, the following stick circuit for the route end relay RR⁴ is closed:—beginning at the terminal (+) of the

office battery, front contact 28 of the relay RR⁴, polar contact 27 of the relay RR⁴, neutral contact 44 and polar contact 45 of the relay SMR⁶, polar contact 86 to the left and neutral contact 87 of the relay SMR⁷, polar contact 10 to the right and neutral stick contact 72 of the relay RR⁴ through the lower winding of this relay RR⁴ to the other terminal (—). The relay Z7 will of course follow relay SMR⁷ and will cause the switch machine SM1 and cross-over 7 to be reversed and cause relay WP7 to be operated to the left. With the relays RR¹, RR⁴ and WP6 now energized to the right, and with the relay WP7 energized to the left the following energizing circuit for the signal relay G1 is closed:—beginning at the terminal (+) of the office battery, front contact 90 of the push button PB⁴, polar contact 91 to the right and neutral contact 92 of the relay RR⁴, neutral contact 93 and polar contact 94 to the left of the relay WP7, polar contact 55 to the right and neutral contact 56 of the relay WP6, neutral contact 57 up and polar contact 58 to the right of relay RR¹, wire 59, winding of the relay G1 to the other terminal (—).

With the signal relay G1 energized the signal S¹ will assume the clear, caution or stop position depending on traffic conditions in advance of signal S¹ over the route just set up, namely, the route starting on track section 1, passing over cross-overs 7 and continuing over track section 2 to the right of the signal S⁴. This route may, of course, be relinquished by the operator's returning his entrance turn button E¹ to its normal position.

If the operator now desires to set up a route from right to left, starting at the signal S³ and terminating to the rear of the signal S², he will operate his entrance button E³ to the left. This will result in energization of the relay RR³ to the left. The operator will next depress the push button PB² as a result of which the relay RR² will be energized to the left. With the route end relays RR³ and RR² energized the following energizing circuit for the relay SMR⁶ is closed:—beginning at the terminal (+) of a battery, contact 120 of route end relay RR³, front contact 121 of route end relay RR² through normally closed contact 122 of the emergency switch machine lever SML⁶, through the reverse winding R of the switch machine relay SMR⁶, through the back contact 123 of the relay SMR⁶ to the other terminal (—). Since the polar contact 124 will operate more quickly than will the neutral contact 123, the energizing circuit just traced will be shifted from the back contact 123 to the left-hand polar contact 124 of the relay SMR⁶, thereby resulting in energization of the relay SMR⁶ to the left. The relay SMR⁷ will, of course, be energized in its right-hand position through the following energizing circuit:—beginning at the terminal (+) of a battery, contact 127 of the relay RR², front contact 128 of the relay RR⁴, normally closed contact 41 of the emergency switch machine lever SML⁷, through the normal winding N of the relay SMR⁷, through the polar contact 109 assuming its right-hand position to the other terminal (—). With the relay SMR⁷ energized to the right the switch machine SM1 will, of course, operate the cross-over 7 back to its normal position. With, however, the relay SMR⁶ energized to the left the relay Z6 will be energized to the left thereby operating the switch machine SM6 to its reverse position. As soon as the cross-over 6 has assumed its full reverse locked position the switch machine repeater relay WP6 will as

sume its left-hand energized position. With the relays RR³ and RR² now energized to the left, with the relay WP6 energized to the left, and with the switch machine repeater relay WP7 energized to the right, the following energizing circuit for the signal relay G3 is closed:—beginning at the terminal (+) of the office battery, normally closed push button contact 101 of the push button PB², polar contact 98 to the left and neutral contact 97 of the relay RR² up, neutral contact 96 up and polar contact 95 of the switch repeater relay WP6 to the left, polar contact 54 to the right and neutral contact 53 of the relay WP7 up, neutral contact 52 up and polar contact 51 of the relay RR³ to the left, wire 62, winding of the relay G3. With the relay G3 now energized the signal S³ will assume a clear, caution or stop condition depending upon traffic conditions in advance of this signal over the route just set up, namely, the route starting at the signal S³, extending to the left on track section 1, over cross-over 6 onto track section 2 to the left of signal S². This route may after the train has passed thereover be relinquished by the operator returning his entrance turn button E³ to its normal position.

In the same manner as just explained traffic may move in the opposite directions over the same track route, as for instance, from signal S² over cross-over 6 to signal S³, or from signal S⁴ over cross-over 7 to signal S².

There is still another route from left to right as well as from right to left which has not yet been mentioned, and which cannot be set up by the use of the turn buttons E¹, E², E³, or E⁴ in combination with push buttons PB¹, PB², PB³, or PB⁴ alone. This route is what is termed as a run-around move and comprises a route over the two cross-overs 6 and 7 reversed in series, so to speak. That is, a route extending from signal S² to signal S⁴ over cross-overs 6 and 7 or extending from signal S⁴ to S² over the same cross-overs. This route may be set up by the operator providing no route is then set up by moving his emergency switch machine levers SML⁶ and SML⁷ to the raised position, as a result of which the switch machine relays SMR⁶ and SMR⁷ are both energized to the left. If the operator, with the levers SML⁶ and SML⁷ both in their raised positions and with relays SMR⁶ and SMR⁷ to the left, operates the entrance turn button E² to the right and depresses the push button PB⁴, the relay RR⁴ will be stuck up through the following stick circuit:—beginning at the terminal (+) of the office battery, front contact 68 of relay RR² up, polar contact 67 of this same relay to the right, neutral contact 84 up and polar contact 85 to the left of the relay SMR⁶, polar contact 86 to the left and neutral contact 87 up of the relay SMR⁷, polar contact 70 to the right and neutral contact 72 up of the route end relay RR⁴, through the lower winding of this route end relay RR⁴ to the other terminal (—). With the relays RR² and RR⁴ now energized to the right and with the switch machine repeater relays WP6 and WP7 energized to the left, as a result of the operator's manual manipulation of levers SML⁶ and SML⁷ resulting in energization of relays SMR⁶ and SMR⁷ to the left, the following energizing circuit for the relay G2 is closed:—beginning at the normally closed push button contact 90 of the push button PB⁴, polar contact 91 and neutral contact 92 of relay RR⁴, neutral contact 93 up and polar contact 94 to the left of relay WP7, polar contact 95 to the left and neutral contact 96 up of the relay WP6, front contact 97 and polar contact 98 to the right

of the relay RR², wire 99, winding of the relay G2 to the other terminal (—). With this energizing circuit for the signal control relay G2 closed, the signal S² may assume the clear, caution or stop condition depending on traffic conditions in advance of the signal S² over the run-around track route passing over cross-overs 6 and 7 and to the right of the signal S⁴. This run-around route will obviously not be set up as a general rule, but may at times be taken advantage of as when repairing or replacing of track rails in the track section 2.

Attention is directed to the fact that where signals governing traffic in opposite directions are located at the same point in the interlocking plant, as is true, for instance, of signals S³ and S⁵, both of these signals S³ and S⁵ may be controlled by the same entrance turn button E³. This is indicated by the provision of an additional route end relay RR⁵ which may be controlled through a contact 130 of the turn button E³ or a contact 131 of the push button PB³ located to the right of the entrance button E³ in the same way as the push button PB³ is located to the left. In this double use of the entrance button E³ the contacts are shown differently than is the case with entrance buttons E¹, E², and E⁴ where only one signal is shown controlled by the same entrance button. More specifically, the contacts of the entrance turn button E³ are so constructed that the contact 43 is connected to the negative terminal of the office battery when the turn button is in its normal, its extreme right-hand or any position intermediate thereof, and is connected to the positive terminal of this battery when the turn button E³ assumes the extreme left-hand position. Similarly, the contact 130 of entrance turn button E³ is connected to the terminal (—) when this button assumes either the normal, the extreme left-hand or any position intermediate thereof, but is connected to the positive terminal of this battery when the turn button E³ assumes the extreme right-hand position.

It should be understood that although the operator has been provided with auxiliary or emergency switch control levers SML⁶ and SML⁷ whereby he may set up any route he desires, these levers SML⁶ and SML⁷ being so constructed that they will remain in the normal middle position, or in either extreme position if operated there and left there, the operator cannot control these relays to a different polar position if they are already energized. For instance, let us assume that the relay SMR⁶ has its normal winding energized, the polar contacts being to the right and the neutral contacts being up, and that the operator lifts the lever SML⁶ and moves the contact 122 into engagement with its stationary contact connected to the (+) terminal of the office battery. The closure of the reverse circuit at this point will be of no avail, because this circuit is open at the left-hand polar contact 124 and is also opened at the back contact 123 of this same relay SMR⁶. In other words, the switch machine control levers SML⁶ and SML⁷ are only available to the operator to control the relays SMR⁶ or SMR⁷ when these relays have not already been energized by the route control route end relays RR¹, RR², RR³, or RR⁴.

Attention is directed to the fact that the control circuit for the switch machine SM6 passes through front contact 135 of the lock relay L and through contacts 136 and 137 of relay Z6. Also, that the switch control circuit for the switch

- machine SM⁷ passes through front contact 138 of lock relay L and contacts 140 and 141 of relay Z⁷. From this it is apparent that the switch machine SM⁶ and SM⁷ cannot be operated unless 5 the relay L is energized. It should also be noted that the lock relay L is energized only if all of the signal relays G¹, G², G³, and G⁴ are deenergized and then only if the track circuits containing track relays T¹ and T² are unoccupied.
- 10 Since switch machine control relays SMR⁶ and SMR⁷ are so constructed that if one of their energizing windings N or R is energized the other one winding cannot be energized, a certain feature of interlocking is provided which is highly desirable. For instance, let us assume that a route 15 has already been set up starting at the signal S¹ and terminating at the signal S⁴, namely, with the relay SMR⁶ energized to the right and with the relay SMR⁷ energized to the left, and let us 20 further assume that the operator attempts to set up traffic in conflict therewith from signal S³ to signal S². The operation of the entrance button E³ to the left and the depression of the push button PB², although this operation will 25 result in energization of the relays RR³ and RR², will not result in a new route. This is true because even though contact 79 of relay RR² and contact 40 of relay RR³ are closed and do connect the positive terminal of the office battery 30 to the upper winding N of the relay SMR⁷, this relay SMR⁷ will not be operated because its polar contact 109 is to the left breaking one of the paths through winding N and the neutral contact 42 is in its raised position thereby breaking 35 the other partial circuit for the normal winding N, so that the relay SMR⁷ is not operated. Obviously, if the relay SMR⁷ cannot be operated to set up the second route the switch repeater relay WP⁷ cannot be operated and the route circuit for such second route cannot be closed at 40 the contacts of the switch repeater relay WP¹. What has been said about the normal circuit for relay SMR⁷ including contacts 79 and 40 of relays RR² and RR³ is also true of the reverse 45 circuit for relay SMR⁶ including contacts 120 and 121 of these same relays RR² and RR³, so that both of relays SMR⁶ and SMR⁷ remain energized as they were and the route from signal S¹ to signal S⁴ will not be disturbed. The feature that the 50 relays SMR⁶ and SMR⁷ cannot be energized to a different polar position when once energized, unless the energizing circuit is first broken, constitutes one of the principal interlocking features in this system in preventing a second conflicting 55 route from being set up. This is true because a conflicting route invariably involves the operation of switch points to a different position. This same interlocking feature, however, permits parallel routes involving the same cross-overs to be 60 set up, this is true because for setting up routes in parallel the cross-overs will assume the same position for both routes. In other words, applicant's interlocking feature, which to a certain extent resides in the peculiar and novel circuits for 65 controlling the switch machine relays, affords interlocking against the actual changing of a route, but permits parallel routes on adjacent tracks and having cross-overs in common therewith to be set up.
- 70 The applicant has thus provided a route relay which defines each end of each track route portion, and he has provided a route circuit for sticking up one of these route relays through a front contact of the other route relay so that 75 only momentary operation of the push button,

which defines the exit point of the route, is necessary. He has provided a plurality of circuits in multiple for operating switch and cross-over points, the circuit organization being such that the first control circuit for such switch machine 5 relay closed is the dominating one and the subsequent closure of other control circuits at the control point therefor are of no avail, and he has further provided signal selecting route circuits which can be closed only if two route end 10 relays defining a particular route are energized and providing all of the switches contained in such route assume a position to define such route. In addition to this construction the applicant's system is such that the operator need not take 15 into consideration the number of switches in a route to be set up, nor the position which they assume, for all that the operator is called upon to do is to operate an entrance turn button at the entrance end of the route he desires to set up 20 and to momentarily depress an exit push button at the exit end of such route. Attention is also particularly directed to the normally closed push button contacts 50, 61, 98, and 101 included in the various route signal circuits for relays G¹, 25 G², G³, and G⁴. These normally closed push button contacts are provided to require the operator to return his exit push button to its normal position before the signal governing traffic over the route in question can actually assume its 30 proceed condition.

It is to be understood that certain features of the system may be dispensed with. For instance, if the push buttons non-spring returned the route circuit for sticking up one route relay through a front contact of the other might be dispensed with. Also, if desired, the emergency levers may be omitted, and the push button contacts in the signal relay circuits may be omitted. Also, any suitable approach and release locking 40 such, for instance, as shown in said prior application of S. N. Wight may be used, if desired. Also, instead of employing route end relays, as shown, manually operable contacts may be used in place thereof in which case the contacts will 45 be three-position and not polar and neutral. The double throw contacts operated directly by the levers SML⁶ and SML⁷ are preferably constructed make-before-break, so that an energized coil of the associated relay cannot be deenergized, 50 and if desired the normally closed contacts thereof may be entirely dispensed with, in which event the control circuits extending from route end relay contacts are connected directly to the proper winding of the associated relay. 55

Having thus shown and described one rather specific embodiment of the invention and having shown this embodiment of the invention applied to a rather simple interlocking system, it is desired to be understood that the particular embodiment, as well as the simple interlocking system to which it has been shown applied, have been selected merely to afford description of the invention and its underlying principles, rather than give the scope thereof; and that various changes, 65 modifications, omissions and additions may be made in accordance with well known signal practice to adapt the invention to other track layout, other types of signals, control buttons or the like, all without departing from the spirit or scope of 70 the invention or the idea of means underlying the same, except as demanded by the scope of the following claims.

What I claim as new is:

1. In an entrance-exit type interlocking sys- 75

- tem, the combination with a track layout having a plurality of routes over portions of track between signals governing train movement in the same direction, each of said routes including one or more switches and many of which have entrance or exit points at signal locations in common, a route end relay for each signal location, a switch machine for each of said switches, a switch machine control relay for each switch machine, manually operable means for controlling said route end relays, circuits for controlling said switch machine control relays by said route end relays, each of said switch control relays having energizing circuits separate from those for energizing other switch control relays, each of said energizing circuits for each switch control relay belonging individually to one of the routes over the corresponding switch and including contacts of the route end relays for the opposite ends of such route, and a signal control circuit for each route including contacts reflecting the positions assumed by the switches therein and contacts of the route end relays at the entrance and exit ends thereof.
2. In an entrance-exit type interlocking system, the combination with a track layout having a plurality of routes over portions of track between signals governing train movement in the same direction, each of said routes including two or more switches or cross-overs and many of which have entrance and exit points at signal locations in common, a route end relay for each signal location, a switch machine for each of said switches and cross-overs, a switch machine control relay for each switch machine, manually operable means for controlling said route end relays independently of the conditions of said switch machine control relays, circuits for energizing said switch machine relays of said switch machines in multiple by said route end relays, each circuit including contacts of two route end relays, and a signal control circuit for each route including contacts reflecting the positions assumed by the switches and/or cross-overs therein and contacts of the route end relays at the entrance and exit ends thereof.
3. In an interlocking system, the combination with a track layout having a plurality of routes each including one or more switches and many routes of which have entrance or exit points in common, a signal for each entrance point, a polar route end relay for each point, switch machines for controlling said switches, a switch machine control relay for each switch machine, control circuits for said switch machine control relays each including contacts of two route end relays, two manually operable means at each point one for energizing the associated route end relay to a polar position to govern traffic into a route at that point and the other to energize such route end relay to a polar position to govern traffic out of a route at that point, and a signal control circuit for each route including contacts reflecting the positions of switches in such route, the contacts of a route end relay energized to an entrance position and the contacts of a route end relay energized to an exit position.
4. In an interlocking system, the combination with a track layout having a plurality of routes each including one or more switches and many routes of which have entrance or exit points in common, a signal for each entrance point, a polar route end relay for each point, switch machines for controlling said switches, a switch machine control relay for each switch machine, control
- circuits for said switch machine control relays each including contacts of two route end relays, two manually operable means at each point one for energizing the associated route end relay to a polar position to govern traffic into a route at that point and the other to energize such route end relay to a polar position to govern traffic out of a route at that point, and a signal control circuit for controlling the signal at the entrance of such route including contacts reflecting the positions of switches in such route, the contacts of a route end relay at the entrance end of such route energized to an entrance polar position and the contacts of a route end relay at the exit end of such route energized to an exit polar position.
5. In an interlocking system, the combination with a track layout having a plurality of routes each including one or more switches and many routes of which have entrance or exit points in common, a signal for each entrance point, switch machines for controlling said switches, a polar route end relay for each point, a normal circuit for each switch machine including in series the front contacts of two route end relays defining a route including the track switch controlled by such switch machine in its normal position, a reverse circuit for each switch machine including in series the front contacts of two route end relays defining a route including the track switch controlled by such switch machine in its reverse position, manually operable means for controlling said polar route end relays, and a signal control circuit for governing the signal at the entrance of a particular route including contacts reflecting the polar energized conditions of the polar route end relay at the entrance and exit end of such route and contacts reflecting the positions assumed by track switches in such route.
6. In an interlocking system, the combination with a track layout having a plurality of routes each including one or more switches and many routes of which have entrance or exit points in common, a signal for each entrance point, switch machines for controlling said switches, a polar route end relay for each point, a normal circuit for each switch machine including in series the front contacts of two route end relays defining a route including the track switch controlled by such switch machine in its normal position, a reverse circuit for each switch machine including in series the front contact of two route end relays defining a route including the track switch controlled by such switch machine in its reverse position, a manually controlled entrance button and a manually controlled exit button for each point; a circuit for each route end relay to energize it to an entrance polar position including a contact of the associated entrance button; a circuit for each route end relay to energize it to an exit polar position including a contact of the associated exit button; a stick circuit for each route end relay closed only if such route end relay is energized to its exit polar position and then only if another route end relay is energized to an entrance polar position; and a signal control circuit for governing the signal at the entrance of a particular route including contacts closed when the entrance route end relay for such route is energized to the entrance polar position, including contacts closed when the exit route end relay is energized to the exit polar position and contacts reflecting the positions assumed by track switches in such route.

7. In an interlocking system, the combination with a track layout having a plurality of routes each including one or more switches and many routes of which have entrance or exit points in common, a signal for each entrance point, switch machines for controlling said switches, a polar route end relay for each point, a control relay for each switch machine; a normal circuit for each control relay including in series the front contacts of two route end relays defining a route including the track switch controlled by that control relay, a manually controllable entrance button and a manually controllable exit button for each point; a circuit for each route end relay to energize it to an entrance polar position including a contact of the associated entrance button; a circuit for each route end relay to energize it to an exit polar position including a contact of the associated exit button; a stick circuit for each route end relay including its own contacts closed only if such relay assumes the exit polar energized position, contacts of the entrance route end relay closed only if such entrance route end relay is energized to the entrance polar position and contacts of the control relays governing the switches in such route assuming a position to set up such route; and a circuit for controlling the signal at the entrance end of such route governing the movement of traffic into such route including contacts closed only if the switches in such route assume a position to set up such route and the route end relays defining the ends of such route assume respectively the entrance polar and the exit polar 35 positions.

8. In combination, a polar neutral relay having polar contacts and neutral contacts, a normal winding for operating the polar contacts to the normal position and for picking up the neutral contacts, a reverse winding for operating the polar contacts to the reverse position and for picking up the neutral contacts, a circuit for said normal winding including in multiple a back neutral contact and a normal polar 40 contact of said relay, and a circuit for said reverse winding including in multiple a back neutral contact and a reverse polar contact, whereby said normal circuit cannot be closed if said relay is energized reverse and said reverse circuit cannot be closed if said relay is energized to its normal position.

9. In combination, a polar neutral relay having polar contacts and neutral contacts, a normal winding for operating the polar contacts to the normal position and for picking up the neutral contacts, a reverse winding for operating the polar contacts to the reverse position and for picking up the neutral contacts, a circuit for said normal winding including in multiple a back neutral contact and a normal polar contact of said relay, a circuit for said reverse winding including in multiple a back neutral contact and a reverse polar contact, a plurality of contacts for applying energy to said normal circuit, and a plurality of contacts for applying energy to said reverse circuit, whereby said normal circuit cannot be closed if said relay is energized reverse and said reverse circuit cannot be closed if said relay is energized to its normal position.

10. In an interlocking system, the combination with a track layout having a plurality of routes each including two or more track switches and many routes of which have entrance or exit points in common, a signal for each entrance point, switch machines for controlling said

switches, manually controllable contacts for each of said entrance and exit points, a normal control circuit for controlling each switch machine including in series a manually controlled contact for the entrance point and a manually controlled contact for the exit point of each route including the track switch controlled by said switch machine in the normal position, a reverse control circuit for controlling each switch machine including in series a manually controlled contact for the entrance point and a manually controlled contact for the exit point of each route including the track switch controlled by said switch machine assuming its reverse position, said normal and reverse control circuits for each switch machine being separate from and energized independently of the circuits for other switch machines, and a circuit for clearing the signal governing the entrance of traffic into such route effective when the manually controlled contacts for the entrance and exit points of such route are operated and contacts reflecting the positions of the track switches in such route reflect that such route is set up.

11. In an interlocking system, a track layout having a plurality of routes formed by one or more track switches and certain of such routes having entrance or exit points in common, manually operable means for each route end, relay means for each route end, circuit means for each said relay means controlled only by said manually controlled means for that route end for at any time initially energizing that said relay means, switch control relays for the track switches selectively and jointly energized in multiple by those of said relay means at the ends of routes including such track switches for setting up such routes, and stick circuit means for each said relay means closed, when such relay means is energized for the exit end of a route and energized dependent upon said energized switch control relays for that route and dependent upon the condition of said relay means at the entrance end of such route.

12. In combination, a polar-neutral relay having polar and neutral contacts, a first control circuit for said relay including in multiple a back contact of said relay and a polar contact of said relay in one position, a second control circuit for said relay including in multiple a back contact of said relay and a polar contact of said relay in the opposite position, and means for at times energizing said first or said second control circuits, said energization of said first circuit causing magnetic flux of one polarity and said energization of said second circuit causing magnetic flux of the opposite polarity in said relay, whereby said polar contacts are actuated to opposite positions depending upon which of said control circuits is energized.

13. In combination, a polar-neutral relay having two windings differentially connected and having polar and neutral contacts, said polar contacts moving to one position when one winding is energized and moving to the other position when the other winding is energized, a source of potential, circuit means for connecting one terminal of said one winding to one terminal of said source through a back contact of said relay in multiple with a polar contact of said relay in said one position, circuit means connecting one terminal of said other winding to said one terminal of said source through a back contact of said relay in multiple with a polar contact of said relay in said other position, and

means for selectively connecting the other terminals of said windings to the other terminal of said source, whereby the first of said windings to be energized causes the polar contacts of said 5 relay to be operated to corresponding positions and the picking up of the neutral contacts and thereafter prevents the energization of the opposite winding.

14. In an interlocking system, a track layout 10 having a plurality of routes formed by one or more track switches and particular ones of such routes having common entrance or exit points, manually operable contact means for each route end, switch control relay means for each of said 15 track switches for operating the corresponding track switch to normal or reverse positions when selectively energized, a relay for each route end, a pick up circuit for each said relay controlled only by said manually operable contact means 20 for the corresponding route end, means including said relays and said manually operable contact means for selectively energizing said switch control relay means initially for a particular route upon the actuation of said manually operable contact means for the opposite ends of 25 that route whereby that route is set up through the track layout, and a stick circuit for each said relay at the exit end of a particular route set up selectively made up by said switch control relay 30 means then selectively energized and dependent upon said manually operable contact means at the entrance end of that particular route.

15. In an interlocking system, a track layout 35 having a plurality of routes formed by one or more track switches and particular ones of such routes having common entrance or exit points, signals for governing traffic over said routes, manually operable contact means for each route end, switch control relay means for each of said 40 track switches for operating the corresponding track switch to normal or reverse positions when selectively energized, a relay for each route end, a pick up circuit for each said relay controlled only by said manually operable contact 45 means for the corresponding route end, means including said relays and said manually operable contact means for selectively energizing said switch control relay means initially for a particular route upon the actuation of said manually operable contact means for the opposite 50 ends of that route whereby that route is set up through the track layout, a stick circuit for each exit relay at the exit end of a particular route set up selectively made up by said switch control relay 55 means then selectively energized and dependent upon said manually operable contact means at the entrance end of that particular route, and circuit means for clearing the signal at the entrance to a route set up only when the exit relay at the exit of that route is picked up.

16. In a system for governing the operation of track switches and signals of a railway track layout, a portion of track having an entering signal governing traffic over a main route including 60 said track portion and over other routes set up by track switches included in said track portion, a control panel having the track layout represented thereon, a manually operable entrance button on said panel associated with said entering signal, a self-restoring exit button associated with the exit end of said main route, an exit relay associated with said exit button, a pick up circuit for said exit relay directly closed by said 65 exit button, route establishing means rendered 70

effective to operate said track switches to set up said main route and to clear said entering signal in response to the operation of only said entrance button and said exit button and said means remaining effective only so long as said exit relay 5 is maintained energized, and stick circuit means for said exit relay closed only after the response of said route establishing means.

17. In an interlocking system of the entrance-exit type, a track layout having a plurality of 10 routes formed by power operated track switches, a control machine having a control panel, manually operable control means on said panel for the opposite ends of the routes of said track layout, relay means for each of said manually operable control means and energized at any time in response to the actuation of its control means, switch control means for said power operated track switches responsive to the energized condition of the relay means for the opposite ends of 15 a route to set up that route and thereafter being unresponsive to the energized condition of a relay means at the end of a conflicting route, and stick circuit means for each of said relay means effective to maintain such relay means energized, 20 when it is energized for the exit end of a route, dependent upon said relay means for the entrance end of such route, said stick circuit means becoming effective only after said switch control 25 means for each of the track switches in that route have responded.

18. In an interlocking system for railroads of the entrance-exit type, a track layout having a plurality of routes each of said routes including one or more track switches with signals for governing traffic into said routes, a manually operable contact means for the opposite ends of said routes, route end relay means for the opposite ends of said routes and each being directly controlled by said manually operable contact means for its route end so as to be responsive to such contact means at any time, switch control means for each of the track switches and each controlled by the route end relay means for the opposite ends of the routes in which the associated track switch is included in such a manner that the actuation of the route end relay means for the opposite ends of a particular route operates such track switch to a proper position for that particular route and thereafter prevents the operation of such track switch to a different position upon the operation of a route end relay means for any of the other routes in which such route may be included, circuit means for maintaining energized the route end relay means for the exit end of a route dependent upon the route relay means for the entrance end of a route only provided the switch control means for each of the track switches have responded to the route relay means for the opposite ends of such route, and signal control means for clearing the signal at the entrance to a route in response to the actuation of the route end relay means at the opposite ends of such route only provided the track switches of such route actually have established that route.

19. In a system for governing the operation of track switches and signals, a portion of track having an entering signal governing traffic over a main route including said track portion and over other routes set up by track switches included in said track portion; a manually operable 65 entrance button for said entering signal; a self-restoring exit button for the exit end of said main route; an exit relay associated with said exit button; a pick up circuit for said exit relay directly closed by said exit button; switch control 70

relays for the several track switches governing the normal and reverse operation of said track switches; circuit means including contacts of said exit relay for selectively energizing said 5 switch control relays for the several track switches in multiple to cause the operation of the track switches to set up said main route, said circuit means being rendered effective in response to the operation of only said entrance button and said

exit button and remaining effective only so long as said exit relay is maintained energized; stick circuit means for said exit relay closed only after the response of said switch control relays; and circuit means for clearing said entering signal in response to the operation of only said entrance button and said exit button. 5

CHARLES S. BUSHNELL.
